Application June 14, 1946, Serial No. 130,728

Term of patent 14 years

(Cl. D62—2)

To all whom it may concern:

Be it known that we, John W. Baur and Eric Gustafsson, both citizens of the United States and residing in Chicago, county of Cook, and State of Illinois, have invented a new, original, and ornamental Design for a Spray Gun or the like, of which the following is a specification, reference being made to the accompanying drawings, forming a part thereof.

Fig. 1 is a side view in elevation of a spray gun or the like showing our new design;

Fig. 2 is a front end view of the same;

Fig. 3 is a top plan view of the same;

Fig. 4 is a side view in elevation of the same opposite from that shown in Fig. 1; and

Fig. 5 is a rear end view of the same.

We claim:

The ornamental design for a spray gun or the like, as shown.

JOHN W. BAUR.
ERIC GUSTAFSSON.
